JAMES N. MACRAE, OF STAMFORD, CONNECTICUT, ASSIGNOR TO PETROLEUM HEAT AND POWER COMPANY, OF NEW YORK, N. Y., A CORPORATION OF DELAWARE

IGNITION MECHANISM

Application filed May 12, 1928. Serial No. 277,838.

The present invention relates to ignition systems and particularly ignition systems adapted for use with oil burners and has for one of its objects the provision of a construction wherein the igniter is given a complete revolution to move the same into and out of firing position. It will be appreciated by those skilled in this art that by moving the igniter out of firing position after the same has functioned, carbonizing of the electrodes of the igniter due to oil collecting thereon, or injury to the electrodes from the heat of the burner is eliminated.

In the drawings accompanying this application, Fig. 1 is a view in part sectional elevational view of an installation embodying my invention;

Fig. 2 is a section on the line 2—2 of Fig. 1; and

Fig. 3 shows the drive mechanism.

Referring to the drawings in detail, 1 designates a burner mounted so as to extend into a furnace 2, the forward end of the burner passing through a plate 3 secured to the furnace front.

4 designates a blower for supplying air to the burner and also, if desired, for feeding oil to the burner.

The blower constitutes no part of the present invention nor does the construction of the burner itself and hence these parts will not be described in any detail.

5 designates a spark plug base and 6 a clamping member by which a spark plug 7 is held in the base 5. The base 5 of the plug is rotatably mounted in a bearing member 8 and is clamped therein by bearing cap 9.

The spark plug 7 is provided with two electrodes 10 and 11, these electrodes extending into the furnace a short distance in line with the longitudinal axis of the plug and then being bent outwardly or laterally and finally inwardly toward each other to provide a spark gap 12.

13 designates a driving tube screwed into the clamping member 6, this tube extending rearwardly of the burner to a point adjacent one end of a motor 14. The rear end of the driving tube 13 is provided with a sprocket 15, this sprocket and a sprocket 16 carried by

the armature shaft of the motor 14 carrying sprocket chain 17.

One of the conductors 18 for the plug 7 is attached to the spark plug as indicated at 19 and passes through the driving tube 13 55 and is led upwardly to a transformer 20.

The motor assembly 14 contains the necessary switch mechanism for timing of the delivery of current to the transformer 20, and inasmuch as this construction may be 60 varied within wide limits I have deemed it unnecessary to illustrate the same for the purposes of this application. I may say, however, that the motor 14 is adapted to make a complete revolution each time the same is 65 operated, and on each revolution current is supplied to the transformer 20, the secondary of which supplies current to the spark plug 7.

Initially the electrodes 10 and 11 of the spark plug are in the full line position of 70 Fig. 1, in which position they are offset with respect to the burner 1, i. e., out of the path of fuel issuing from the burner. Upon operation of the motor 14 the electrodes 10 and 11 are rotated through the chain drive, above 75 described, for a complete revolution, passing from the full line position of Fig. 1 to the dotted line position and continuing to the full line position again. In the dotted line position of the electrodes, i. e., with the spark 80 gap in the path of the fuel issuing from the burner a spark is produced across the gap 12 to effect the desired ignition of the fuel.

It will be seen, therefore, that I have provided an ignition apparatus adapted for use 85 with oil burners in which the electrodes of the igniter, when the igniter is operated, make a complete revolution, under the positive drive of the motor 14, coming to rest, however, in a position where the electrodes are out of the 90 path of the burning fuel and hence carbonizing of the electrodes and injury to the electrodes due to the heat of the burner are prevented.

What I claim is:—

1. Ignition apparatus for oil burners, comprising a pair of electrodes and means for moving the electrodes through a complete revolution to pass the same through fuel issuing from the burner.

2. Ignition apparatus for oil burners, comprising a pair of electrodes offset with respect to the burner, and means for rotating said electrodes through a complete revolution to move the same through and out of the path of fuel issuing from the burner.
3. Ignition apparatus for oil burners, comprising a pair of electrodes having a lateral bend, a spark plug and a plug base carrying said electrodes, and means for driving said plug and base through a complete revolution to carry the offset of the electrodes into and out of the path of fuel issuing from the burner.
4. Ignition apparatus for oil burners, comprising a spark plug, a plug base, a clamping member for holding the plug to the base, electrodes for said plug, a driving tube fixed to said clamping member, a sprocket thereon, a motor, a chain drive from the motor to said driving tube provided in part by said sprocket, operation of the motor driving said plug and base to move said electrodes through a complete revolution into and out of the path of fuel issuing from the burner.

This specification signed this 10th day of May, 1928.

JAMES N. MACRAE.
